DOORCHECK

Filed May 1, 1931

UNITED STATES PATENT OFFICE

SAMUEL HAMMER, OF BROOKLYN, NEW YORK, ASSIGNOR TO UNITED METAL BOX CO. INC., OF BROOKLYN, NEW YORK, A CORPORATION OF NEW YORK

DOORCHECK

Application filed May 1, 1931. Serial No. 534,163.

This invention relates to cabinets and similar structures, and more particularly to medicine cabinets and the like.

The primary object and purpose of my present improvements is to provide the hingedly mounted door of such a cabinet with means which will yieldingly stop or limit the opening movement of the door to a position in right angular relation to the plane of the cabinet body.

It is a more particular object of the invention to provide such a limiting means for the opening swinging movement of the door embodying a movable member mounted on one wall of the cabinet body and spring means co-acting therewith and yieldably resisting movement of said member in one direction, and a slotted link having a slidable connection with said member and a pivotal connection with the inner face of the cabinet door.

It is another important object of the invention to provide a device for the above purpose, the parts of which are of simple construction and may be easily assembled in connection with the cabinet body and the door and which will operate to minimize excessive strain on the slidable stop link, or the door part with which it is connected as well as the hinge connections between said door and the cabinet body.

With the above and other objects in view, the invention consists in the improved cabinet, and in the form, construction and relative arrangement of its several parts as will be hereinafter more fully described, illustrated in the accompanying drawings, and subsequently incorporated in the subjoined claims.

In the drawings, wherein I have shown one simple and practical embodiment of my present improvements, and in which similar reference characters designate corresponding parts throughout the several views,

Figure 1 is a top plan view partly broken away, and illustrating in dotted lines the positions of the parts when the cabinet door is forced beyond its normal full open position;

Fig. 2 is a sectional view taken on the line 2—2 of Fig. 1, and

Fig. 3 is an enlarged sectional view taken on the line 3—3 of Fig. 1.

Referring in detail to the drawings, the cabinet body 5 may be of the usual heavy pressed sheet metal construction as generally employed in medicine cabinets such as are installed in bath rooms. In the illustrated embodiment of the invention, I have shown this cabinet body provided upon its side, bottom and top walls at the front open side of the cabinet with the flange 6. The body of the cabinet extends into the usual opening or mortise provided in the face of the building wall, while the edges of the flange 6 abut closely against the face of the wall around said opening.

Upon the flange 6 at one side of the cabinet body, the door 7 is hingedly mounted as indicated at 8. This door, which need not be herein described in detail, is quite heavy, and carries in its front side a suitable mirror, usually extending over the entire area of the door. This mirror is confined or retained in the door frame by a back plate 9 of sheet metal.

To the back plate 9 of the door near its upper end and adjacent its hinged edge a bracket 10 is rigidly fixed or secured in any suitable manner. To this bracket, one end of the link 11 having a longitudinally extending slot 12 is pivotally connected by the rivet 13. This slotted link has a slidable connection with a yieldingly held movable member mounted on one wall of the cabinet body. In the illustrated embodiment of my invention, I have shown this movable member in the form of a lever 14 which extends transversely upon the upper side of the top wall of the cabinet body. As a simple and practical means for mounting this movable lever, I provide the cover or housing plate 15 having flanged or offset opposite edges welded or otherwise permanently secured to the cabinet wall. A stud or projection 16 is punched from the housing plate adjacent the rear end thereof and is loosely engaged in an opening 17 provided in one end of the lever 14, whereby said lever may have a pivotal movement between the top wall of the cabinet and the plate 15. This lever is yieldingly held in a normal position

by means of a suitable spring 18 which is arranged between one edge of said lever and one of the side flanges on the housing plate 15. The forward edge of this housing plate is provided with a downwardly extending stop lug 19 which limits pivoting movement of the lever 14 against the action of the spring 18.

The other end of the lever 14 projecting forwardly from the housing plate 15 carries a pin 20 extending downwardly therefrom and preferably provided intermediate of its ends with an annular flange or collar 21 moving in a slot 22 formed in the top wall of the cabinet body 5. I prefer to thread the upper end of this pin to receive a separate collar 21 and form said pin at its lower end with an integral head 23. Thus, in assembling, the pin 21 may be readily inserted upwardly through the slot 12 of lever 11 and the slot 22 in the wall of the cabinet, after which the collar 21 threaded upon said pin, and the end of the lever 14 then engaged upon the upper end of the pin and held in connection therewith by the nut 24. However, it will be understood that this specific connection between the lever 14 and link 11 is merely suggestive, and various other means might be adopted for permitting of the relative sliding connection between said link and lever.

In the operation of the device as above described, and from reference to Fig. 1 of the drawings, it will be understood that when the door 7 is in its full normal open position, it extends outwardly at substantially right angles to the plane of the wall face and the cabinet body 5. When such a door is swung open with considerable force, if its movement to such position is definitely limited by a fixed stop, the hinge connection between the door and the cabinet and the connection between the link 11 and the back plate of the door will be placed under excessive strain which may result in breaking or shearing of the rivet connection 13 or bending or distortion of the back plate 9 of the door, as well as distortion of the hinge connections 8 which might seriously interfere with the free swinging movement of the door to its open and closed positions. By means of my invention, this disadvantage of the fixed limiting stop for the movement of the link 11, is overcome, and in the event that the door is swung open with considerable violence, when the link 11 reaches the limit of its movement relative to lever 14 as permitted by the slot 12, the door will move past its normal full open position as indicated by dotted lines in Fig. 1 of the drawings, and in such movement the lever 14 will be swung laterally against the resistance of the spring 18 to the distance permitted by the length of the slot 22. Thus, it will be apparent that such further movement of the door beyond the right angular position with respect to the cabinet will be yieldingly cushioned so that the parts of the door structure and the sliding link connection between the door and lever 14 as well as the hinge connections 8 will be relieved of excessive strains.

From the foregoing, the construction and several advantages of my present improvements will be fully and clearly understood. It will be seen that I have devised a very simple means for protecting the door structure and its mounting against possible serious damage due to abusive use. The device as herein described consists of relatively few mechanical parts of simple form which obviously may be very readily assembled in the manufacture of such cabinets and therefore, will not appreciably add to the cost of such cabinets as heretofore produced in the art. I have found the device as above described to be very effective and reliable in its operation. Nevertheless, it is to be understood that in the adaptation of my invention to cabinets of various forms for different purposes, certain changes in the form and arrangement of the several cooperating elements may be required. It is accordingly to be understood that in practice, I reserve the privilege of incorporating the essential features of the invention in such other alternative mechanical structures as may be fairly considered within the spirit and scope of the appended claims.

I claim:

1. In combination with a supporting wall and a housing plate secured to said wall, a lever projecting at one of its ends beyond one end of the housing plate, a pivotal connection between the other end of the housing plate and said lever, a spring arranged between the housing plate and the wall and coacting with said lever to yieldingly hold the same against pivotal movement from a normal position, said wall having a slot therein, a stop member carried by the projecting end of the lever and extending through said slot, and a slotted link slidably connected with the stop member on the opposite side of said wall with respect to said lever and adapted to be pivotally connected at one of its ends to a door, whereby said spring held lever will be pivotally moved to resistingly limit movement of said link in one direction relative to the supporting wall.

2. In a door stop, a housing plate adapted to be secured to a supporting wall, a lever pivotally mounted at one of its ends on said housing plate and projecting beyond an edge thereof, a stud fixed in the other end of said lever, a link for limiting the opening movement of the door slidably connected with said stud, and spring means coacting with the lever to resist pivotal movement of the same in one direction and yieldingly resist relative pivotal movement between the lever and the link to check the opening movement of the door.

3. A door check comprising a lever and

means for pivotally mounting said lever at one of its ends upon a supporting wall, a stud fixed in the other end of said lever, a link adapted to be pivotally connected at one end with said door and slidably and pivotally movable on said stud, and spring means permitting of the unretarded sliding movement of the link relative to the stud in the opening of the door while yieldingly resisting relative pivotal movement between the lever and said link to yieldingly check movement of the door beyond a predetermined open position.

4. A door check comprising a lever and means for pivotally mounting said lever at one of its ends upon a supporting wall, a stud fixed in the other end of said lever to extend through a slot in the supporting wall and positively limit pivoting movement of said lever on said wall, a link adapted to be pivotally connected at one of its ends to a door and to extend at its other end on the opposite side of said supporting wall with respect to said lever, said link having a slot in which said stud is pivotally and slidably engaged, and spring means coacting with said lever permitting unretarded sliding movement of the link in one direction relative to said stud and thereafter yieldingly resisting relative pivotal movement between the link and said lever to yieldingly check movement of the door beyond a predetermined open position.

In testimony that I claim the foregoing as my invention, I have signed my name hereto.

SAMUEL HAMMER.
